Primary Examiner — Vy N Koenig(57) **CLAIM**

The ornamental design for an air nozzle for hair drier as shown and described.

DESCRIPTION

The file of this patent contains at least one drawing/photograph executed in color. Copies of this patent or patent application publication with color drawing(s) will be provided by the Office upon request and payment of the necessary fee.

1. Air nozzle for hair drier

1.1 : Front

1.2 : Back

1.3 : Left

1.4 : Right

1.5 : Bottom

1.6 : Top

1.7 : Perspective

1.8 : Perspective

The name of this design is air nozzle of hair drier; The design point of this design is the shape.
